UNITED STATES PATENT OFFICE.

BERNHARD DREYFUS, OF NEW YORK, N. Y..

DESIGN FOR A CHENILLE PENDANT.

SPECIFICATION forming part of Design No. 14,265, dated September 11, 1883.

Application filed June 28, 1883. Term of patent 3½ years.

To all whom it may concern:

Be it known that I, BERNHARD DREYFUS, of the city, county, and State of New York, have invented and produced a new and original Design for a Chenille Pendant, of which the following is a full, clear, and exact description.

This new design relates to chenille pendants to be used in ornamenting cushions, lambrequins, table-covers, &c.

Reference is to be had to the accompanying drawing, forming part of this specification, in which a longitudinal view of my newly-designed pendant is shown.

The chenille pendant A is made tapering

from one end to the other, as shown. At the 15 base is placed the tuft B, and at the top a smaller tuft, C, surmounted by a loop, D.

I claim—

The herein-described newly-designed pendant, consisting of a pendant tapered from one 20 end toward the other, and provided with a slung ruff or tuft at both ends, and with a loop at the thinner end, substantially as herein shown and described.

BERNHARD DREYFUS.
